UNITED STATES PATENT OFFICE.

OLIVER W. RANDOLPH, OF McCLURE, OHIO.

INCUBATOR.

SPECIFICATION forming part of Letters Patent No. 660,309, dated October 23, 1900.

Application filed January 4, 1900. Serial No. 359. (No model.)

To all whom it may concern:

Be it known that I, OLIVER W. RANDOLPH, a citizen of the United States, residing at McClure, in the county of Henry and State of Ohio, have invented a new and useful Incubator, of which the following is a specification.

This invention relates to incubators; and one of the principal objects of the invention is to provide in connection with an incubator-body means for discharging fresh air in a heated and moistened condition into the interior of the incubator and distributing or spreading the same from above the egg-tray and over the eggs.

Another object of the invention is to provide efficient means for properly and thoroughly ventilating the incubator and freeing the same from foul air.

Another object is to provide a novel form of egg-tray in connection with an egg-separating frame by means of which the eggs are prevented from coming in contact with each other, the construction at the same time enabling the eggs to be rolled or partially turned over at proper intervals.

The invention also has for its object to provide a novel form of nursery-tray comprising a flexible or fabric bottom and having means whereby the said flexible bottom may be readily and quickly removed and replaced by another piece of fabric.

The invention also contemplates novel means for conveying the water after it has cooled in the main tank back to the boiler or heater, so that it may be reheated and conveyed in the form of moisture back to the interior of the incubator.

Other objects and advantages of the invention will appear in the course of the ensuing description.

The invention consists in an incubator embodying certain novel features of construction and arrangement of parts, as hereinafter fully described, illustrated in the drawings, and incorporated in the claims.

In the accompanying drawings, Figure 1 is a vertical sectional view of an incubator constructed in accordance with the present invention. Fig. 2 is a similar section taken at right angles to Fig. 1. Fig. 3 is a broken perspective view of the hot-water tank, showing also the boiler or heater, the mixing-cham-

ber, and the connections between said parts. Fig. 4 is an enlarged vertical section through the heater. Fig. 5 is a similar view taken through the mixing-chamber. Fig. 6 is a detail perspective view of portions of the egg-tray and egg-separating frame, showing said parts properly associated. Fig. 7 is a fragmentary sectional perspective view of the nursery-tray.

Similar numerals of reference designate corresponding parts in all figures of the drawings.

The body of the incubator comprises in its construction double walls, 1 designating the outer wall, 2 the inner wall, and 3 an intervening air-space between said walls in order that a body of dead or stagnant air may be confined between the inner and outer walls to prevent the temperature within the incubator from being influenced by the outside temperature. The incubator-body thus formed is supported upon suitable legs 4. The front wall of the body is composed of a pair of doors, 5 designating the outer door and 6 the inner door. The outer door is hinged at its lower edge, as indicated at 7, so as to fold downward as it is swung outward, while, on the contrary, the inner door 6 is hung at its upper edge 8 to fold upward, thus facilitating the withdrawal of the nursery-tray hereinafter described.

Arranged in the upper portion of the incubator is a hot-water tank 9, closed on all sides, top and bottom. This tank is preferably shallow in order to economize space, but extends entirely over the egg-tray hereinafter described. Mounted upon the outside of the incubator-body is a double boiler or heater comprising a lower or main section 10 and an upper section 11, the two sections being connected by the heater or boiler tubes 12. Arranged at one side of and adjacent to the heater is a mixing-chamber 13, having at its lower end a fresh-air-inlet pipe 14 and at a point intermediate its ends a steam-supply pipe 15, which communicates with the upper end of the upper section 11 of the double heater, said steam-supply pipe being provided at a point intermediate its ends with a cut-off valve 16 in order to shut off the supply of hot air or steam when it is desired to ventilate the incubator. Adjacent to its upper

end the mixing-chamber has connected thereto a moistener-tube 17, which extends horizontally beneath the hot-water tank 9 and is secured thereto for support by any suitable 5 or convenient means. The moistener-tube 17 extends entirely across the bottom of the hot-water tank and is provided with a right-angular upward extension or vent-pipe 18, which passes through the upper and lower walls of 10 the hot-water tank and projects sufficiently above the tank to receive a stopper 19, which is inserted therein when the apparatus is used for supplying moist air to the interior 15 of the incubator. In operation the steam or hot air passes from the heater through the steam-supply pipe 15 into the mixing-chamber 13 and upward to the moistener-tube 17, thus drawing fresh air up through the air-tube 14 and carrying a sufficient quantity of 20 fresh air with it to the interior of the incubator. Connected with the moistener-tube 17 at intervals are flaring spray-nozzles 20, which open downward just above the eggs and serve to discharge the contents of the 25 moistener-tube in close proximity to the egg-tray.

The double heater or boiler comprises in its lower section an outer cylindrical wall 21 and an inner flue-wall 22, which is of conicocylindrical shape, tapering gradually from its lower end, which is the larger, toward its upper end, thus forming an upwardly-contracting flue for the products of combustion from a suitable burner 23, arranged beneath the 30 heater. The flue-wall 22 and outer wall 21 are sealed at top and bottom by the upper and lower walls 23 and 24, respectively, so as to form an annular water-space 25. The upper section 11 of the heater is also closed on 35 all sides, top and bottom, and comprises an outer cylindrical wall 26 and an inner cylindrical wall 27, which is open at its upper end and which extends downward into and partially through the tapering flue within the 40 lower section 10, so that a portion of the heat will pass upward through the inner flue (designated by 28) and raise the temperature of the contents of the upper section 11. Water is introduced into the upper section through 45 an opening in its upper wall, which is closed by a removable filling-plug 29, the water passing through the boiler or heater tubes 12 into the lower section 10. By the arrangement of flues just described the upward progress of the 50 hot air is impeded and therefore caused to act with greater efficiency on the lower section 10, while at the same time it acts against the bottom of the upper section 11 and also heats the inner wall 27 of the upper section and 55 raises the temperature of the contents of said upper section. The hot air, hot water, or steam, as the case may be, is conveyed from the upper section 11 through supply-pipes 30 and 31, which enter the hot-water tank 9 and 60 are of unequal length, so as to discharge the water at different points within said tank,

thereby equalizing the temperature of the water within the tank.

The lower section of the boiler is provided near its bottom with an extension 32, from which branch pipes 33 diverge upwardly and enter the hot-water tank at that side or end adjacent the heater. The water within the tank 9 as it cools passes outward therefrom through the return water-tubes 33 and is collected in the heater extension 32, whence it passes into the heater and is reheated. In this way a complete circulation is established between the hot-water tank and the heater. The hot-water tank is provided with a vertical regulator-tube 34, through which may freely pass one of the operative parts of an ordinary thermostatic regulator, and the heater is provided with a draw-off cock 35 in order to provide for emptying the water from 75 the heater when the incubator is not in use.

Arranged at or near the bottom of the incubator is a nursery-tray 36, comprising a rectangular metal frame 37, each side bar or end of which comprises an outer upwardly-extending flange 38 and an inner obliquely-disposed flange 39, which inclines upward and outward toward the upright flange 38. A piece of fabric 40 is stretched across the inside of the nursery-tray frame to form a cheap 95 flexible bottom therefor. The edges of the fabric overlap and extend beyond the oblique flanges 39 and lie in the gutter formed between the flanges 38 and 39, in which said edges are confined and clamped by means of binding or retaining strips 41, each of which comprises a flat horizontal body portion and an oblique flange 42, projecting upward and outward from the inner edge thereof, the flange 42 being disposed at substantially the 100 same angle as the flange 39, above described, so as to enable each retaining-strip to act as a wedge for pressing the edges of the fabric bottom beneath and into the angles between the bottom wall of the nursery-tray frame 105 and the inner oblique flange 39 thereof, thereby serving to stretch the flexible fabric bottom 40 across the frame and render the same sufficiently taut to support the weight of the chickens after they are hatched and fall 110 downward from the overlying egg-tray. By the construction above described the retaining-strips may be quickly removed and the fabric bottom taken out of the nursery-tray 115 and cleaned or replaced by a new bottom. 120

By reference to Fig. 7 of the drawings it will be seen that when it is desired to insert a new flexible bottom 40 it is simply necessary to pull upwardly upon the edge of the fabric protruding from under the outer edge 125 of each retaining-strip. The strip will in this manner be tilted slightly and will effect the separation of the contiguous inclined flanges 39 and 42 and will permit the removal of the fabric bottom. When the new bottom has 130 been laid over the frame, the flanged edges of the strips are forced upon the fabric and

under the flanges 39, which serves to stretch the bottom taut. The rear edges of the strips are then forced down, which securely wedges said strips between the flanges 38 and 39 and retains the bottom in place, with its edge drawn sharply around the top of the flanges 39.

Between the hot-water tank and the nursery-tray is interposed the egg-tray 43. The frame of this tray is of open rectangular form, each of the side and end bars thereof being L-shaped in cross-section, as shown at 44, so as to form an upright surrounding rim and inwardly-extending horizontal ledges 45. Upon the ledges 45 are placed egg-troughs 46, preferably formed of sheet metal and provided with upturned and upwardly-diverging or flaring longitudinal flanges 47, between which the eggs are confined. The upper edges of the flanges 47 lie in the same horizontal plane and form rests for an egg separating and rolling frame 48, which is composed of a parallel series of strips or division-pieces 49, intersecting or extending at right angles to each other, so as to form a plurality of individual compartments 50 for the eggs. An egg is placed in each compartment 50 and rests upon the trough 46 and between the flanges 47 thereof, and thus it is impossible for the eggs to come in contact 30 with each other.

The egg-separating frame 48 is sufficiently smaller than the egg-tray 43 to admit of said egg-separating frame being moved bodily, thereby adapting it to act upon the eggs so as to roll or turn the eggs partially over at the proper periods. The egg-separating frame is not attached in any way to the egg-tray, and therefore when the hatching-out process begins the said egg-separating frame 40 may be removed from the egg-tray and, if desired, withdrawn from the incubator. Before doing so, however, it may be desirable to roll the eggs laterally from the troughs 46 into the spaces between the troughs, so that 45 the eggs will rest on the adjacent edges of parallel troughs. By this arrangement the chickens as they hatch may drop through the space between the troughs and fall upon the flexible bottom of the nursery-tray beneath.

50 In order to ventilate the incubator, the cut-off valve 16 may be closed and the stopper 19 removed from the vent-pipe 18. This will allow the bad air within the incubator to pass upward through the nozzles 20 into the moistener-tube 17 and thence outward through the vent-pipe 18, or steam may be allowed to pass through the moistener-tube 17, whereupon it will act by suction to draw the air from the incubator and force it outward through the 55 vent-pipe 18, at the same time drawing inward fresh air through the air-pipe 14 and the holes 14^a in the end of the body or casing, said air-inlet holes 14^a being shown by Fig. 2. It will thus be seen that I have provided a 60 simple means for introducing moistened air into the incubator for ventilating the incubator and freeing the same from bad air and

also for creating a complete circulation of water between the heater or boiler and the hot-water tank. It will also be seen that I 70 have provided an egg-tray in which the eggs may be easily turned partially over and by means of which the chickens as they hatch may drop through the egg-tray upon the nursery-tray beneath. It will also be seen 75 that the nursery-tray is provided with a removable flexible bottom and that such bottom may be quickly removed and replaced whenever necessary.

From the foregoing it is thought that the 80 construction, operation, and many advantages of the herein-described invention will be apparent to those skilled in the art without further description, and it will be understood that various changes in the size, shape, 85 proportion, and minor details of construction may be resorted to without departing from the spirit or sacrificing any of the advantages of the invention.

Having thus described the invention, what 90 is claimed as new, and desired to be secured by Letters Patent, is—

1. The combination with an incubator having an egg-tray, and a heater situated exteriorly of the incubator, of a mixer having a 95 steam-pipe connection with the heater, a fresh-air inlet to the mixer at one side of the steam connection, and a moisture-delivery tube connected to the mixer at a point to receive an admixture of steam and air, said delivery-tube 100 arranged partly in the incubator and having a number of delivery-ports at points intermediate of its length, as set forth.

2. The combination of an incubator having an egg-tray and a water-tank, a heater having water connection with the tank, a mixer provided with a fresh-air inlet and with a steam connection with the heater, and a moisture-delivery pipe connected to the mixer and arranged between the tank and the egg-tray, said delivery-pipe provided at points intermediate of its length with a number of ports which face toward the egg-tray, as set forth.

3. The combination with an incubator, of 115 an exteriorly-arranged heater, an exteriorly-arranged mixing-chamber, a steam-pipe affording communication between the heater and mixing-chamber, a cut-off valve in said pipe, a moistener-tube leading from the mixing-chamber to the interior of the incubator, and having orifices located above the egg-tray, and a vent-pipe forming an extension of said moistener-tube, provided with a stopper, substantially as and for the purpose 120 125 specified.

4. The combination with an incubator, of an exteriorly-arranged heater, a mixing-chamber at one side of the heater, a pipe leading from the top of the heater to the mixing-chamber and communicating with the latter at a point intermediate its height, an air-supply tube communicating with the lower end of the mixing-chamber, and a moistener-tube com-

municating with the mixing-chamber above the entrance of the pipe which communicates with the heater, said moistener-tube leading to the interior of the incubator, and provided 5 with discharge-orifices, substantially as described.

5. The combination with an incubator, of a tank arranged in the upper portion thereof, an exteriorly-arranged heater comprising upper and lower sections placed in communication by connecting-tubes, the lower section having an upwardly-contracting conico-cylindrical inner flue-wall arranged to form a water-chamber which increases in transverse 15 area from the bottom upwardly, and the upper section having a cylindrical inner wall which extends downward into the flue of the lower section, a lateral extension near the bottom of the heater, upwardly-diverging return-tubes leading from said extension to the hot-water tank, and supply-pipes leading from the upper section of the heater to the interior of the hot-water tank, substantially 25 as and for the purpose specified.

25 6. The combination with an incubator, of an egg-tray comprising a frame, a plurality of parallel troughs arranged therein to leave intervening spaces, and an egg-separating frame supported on said troughs and adapted 30 to slide thereon, said egg-separating frame being divided into individual egg-compartments open at top and bottom, substantially as described.

7. The combination with an incubator, of an egg-tray comprising a plurality of parallel 35 troughs spaced apart and having upturned and obliquely-disposed flanges along their longitudinal edges, and an egg-separating frame resting and adapted to slide thereon and having individual egg-compartments, the said 40 egg-separating frame being removable from the egg-tray, substantially as described.

8. As a new article of manufacture, a nursery-tray for incubators comprising a rectangular frame provided with vertical flanges 45 around its outer edges and with inclined flanges substantially parallel with the vertical flanges but located at the inner edges of the frame, a flexible bottom having its edges extended over the inclined flanges of the 50 frame and across the face of said frame between the flanges, and retaining-strips disposed upon the edges of the flexible bottom between the flanges of the frame, said retaining-strips being provided with inclined flanges 55 in contact with the flexible bottom where it conforms to the inclined flanges of the tray-frame.

In testimony that I claim the foregoing as my own I have hereto affixed my signature in 60 the presence of two witnesses.

OLIVER W. RANDOLPH.
